UNITED STATES PATENT OFFICE

2,436,700

CAVITY RESONATOR OSCILLATOR

Sterling C. Spielman, Huntingdon Valley, Pa., assignor, by mesne assignments, to Philco Corporation, Philadelphia, Pa., a corporation of Pennsylvania

Application January 29, 1944, Serial No. 520,296

2 Claims. (Cl. 315—39)

1

This invention has to do with the problem of maintaining constant, as nearly as possible, the frequency of electrical oscillations generated by an ultra high frequency oscillator, particularly one of the type comprising a resonant cavity and a so-called "lighthouse" type triode.

A resonant cavity oscillation generator, such as that hereinafter described, is designed to function at extremely high frequencies and is often employed, as for example on aircraft, under conditions which entail subjection to a wide range of temperature variations while precluding the provision of temperature-controlled housing means capable of shielding the generator against such temperature variations.

The primary object of the invention is to provide simple and dependable frequency-regulating means operative to counteract the influence of temperature changes tending to cause frequency deviations; and it is a further object to accomplish the above end without adding substantial bulk or weight to the generating equipment.

The invention can best be described and explained by referring to the drawings wherein,

Fig. 1 is a longitudinal sectional view of a resonant cavity oscillation generator incorporating a preferred embodiment of the invention; and

Fig. 2 is a fragmentary sectional view corresponding in general to the upper end portion of Fig. 1 and illustrating a modification.

The ultra high frequency oscillation generator depicted in Fig. 1 includes a resonant cavity, which is identified as a whole by reference numeral 10, and a three-electrode vacuum tube or triode 11 of the so-called "lighthouse" type. The latter comprises a base 12 having a number of contact prongs 13, a glass envelope 14, an anode 15, a control grid 16, and a cathode 17 of the heater type. The anode is a solid cylindrical slug supported on a flat metal ring 18 from which it extends upwardly to form a contact terminal 15a and downwardly within the envelope of the tube to a plane closely adjacent and parallel to but out of contact with grid 16.

The grid consists of a flat woven wire network extending crosswise of the envelope, between the anode and cathode, and supported on a surrounding flat metal ring 19 which is spaced from ring 18 by the glass tube 14a constituting a part of the tube envelope. Ring 18 is soldered or brazed to anode 15 and is sealed to the upper end of glass tube 14a, and ring 19 is sealed to the lower end of glass tube 14a and also to the upper

2

end of a second glass tube 14b upon which it rests and which, together with tube 14a, forms the glass portion of the envelope. The glass of which tubes 14a and 14b are composed is of a variety which does not expand or contract substantially when subjected to the ambient temperature variations to be expected in the course of normal operation. The "lighthouse" tube—which may be a standard No. 464 or 446—is characterized by extremely close spacing between grid and anode and between grid and cathode—which close spacing is necessitated by the requirement that electron transit time be as short as possible. But this close spacing of said electrodes, amounting in each case to only a few thousandths of an inch, is a detriment with respect to the maintenance of constant frequency because any variation of temperature of the anode or cathode or both, such as would be consequent upon marked changes of ambient temperature, or of load, will cause changes in the inter-electrode spacings which, though dimensionally small, amount to a substantial percentage of the total spacing and thus tend to bring about relatively large capacity variations which result in correspondingly large frequency deviations. The purpose of the present invention is to counteract and offset the frequency-varying effect of the aforementioned variations of inter-electrode spacing, as well as those arising from other possible variations in the system, when said variations are due to changes of ambient temperature, or internally-generated temperature, and thus to maintain the frequency within a narrow range of deviation. How this is accomplished will presently be explained.

The resonant cavity 10 is a combination of coaxial transmission line sections and comprises an outer metallic tubular shell 20 closed at its upper end by a disk 21 of insulating material and at its lower end by the base of tube 11 and a ring 22 which is secured to the shell and centrally apertured to receive said tube base. Ring 22 includes a band-like annular portion 22a which is slotted axially so that it is capable of being contracted into gripping engagement with the tube base by means of a split clamping ring 23. The "lighthouse" tube can be withdrawn and replaced upon loosening ring 23, which is normally held under contraction by a clamping screw 24. Mounted within the cavity, concentrically with the shell 20, is a metal cylinder 25, known as a grid cylinder. This is slotted longitudinally at its lower end to render said lower end expansible 55 to receive tube 11; and it is internally grooved

circumferentially at 26 to engage and made electrical contact with the peripheral edge of grid ring 19. The present invention is not directly concerned with the function of grid cylinder 25, but it is thought appropriate to mention that said cylinder forms a part of the frequency-determining resonant network and constitutes a conductor which is common to several sections of co-axial line which will be found to be present upon analysis of the structure as an ultra high frequency generator.

Disk 21 is bored centrally to receive a metal bushing 27 which is internally threaded to engage the external thread 28 of an elongate metal rod 29, known as the plate rod, which extends downwardly and is adapted at its lower end to withdrawably engage the cylindrical terminal portion 15a of anode 15 and thereby effect electrical connection with the anode. The adaptation of the lower end of the plate rod to render it withdrawably engageable with said anode terminal is accomplished by boring said lower end to form a thin resilient cylindrical wall, inserting a contact bushing 30 into the bore and securing the same by silver soldering or brazing, and then longitudinally slotting the bored portion, together with bushing 30, to form an expandable socket into which the cylindrical terminal 15a is easily insertable. To the upper end of plate rod 29 is attached a knob 31 by means of which the rod can be rotated and thus caused to move up or down by virtue of thread 28; and the purpose of so doing is to effect tuning adjustments of the generator.

Secured to plate rod 29 and concentric therewith, is a cup-like metal element 32 which is known as a plate choke. This constitutes, in conjunction with shell 20, a quarter-wave line having the characteristics of a short circuit and operating in the same manner as a complete conductive closure of the space between plate rod 29 and the inside surface of the shell 20.

The plate rod constitutes the axial conductor of a co-axial line, of which shell 20 is the outer conductor, and said rod also forms a second co-axial line section in conjunction with the grid cylinder.

A probe 33, which need not be described, serves as the medium for withdrawing high frequency energy from the cavity; and a terminal 34 provides means for connecting a plate current supply source to the plate rod.

Up to this point, the description of Fig. 1 embraces only a previously known structure which operates satisfactorily under favorable conditions but was found to be excessively unstable as to output frequency when employed in aircraft and subjected to wide ambient temperature changes, without any supplemental provision, such as a temperature-controlled housing, capable of serving as a shield against such ambient temperature variations.

The problem presented was to reduce to a permissible value or, if possible, completely alleviate the aforementioned frequency instability; and to do so without resorting to a protective housing which would increase the weight and bulk of the equipment besides introducing certain inconveniences which it was desirable to avoid.

The solution of the problem arose from my observation that increased ambient temperature caused the frequency to decrease. Having in mind that a movement of plate rod 29 downwardly, as viewed in Fig. 1, relatively to anode

terminal 15a, would give rise to an increase in the frequency of oscillation and vice versa, I conceived that it might be feasible to take advantage of the longitudinal expansion and contraction of plate rod 29, which would inevitably accompany rising and falling ambient temperatures, respectively; and that such movements might be made capable of and sufficient to largely or wholly offset the aforementioned frequency deviations. It is apparent that since plate rod 29 and shell 20 were heretofore both composed of copper or brass and therefore possessed the same coefficient of expansion, little or no movement of rod 29 relatively to anode terminal 15a would occur in response to ambient temperature changes; but I perceived that if a sufficient and appropriate difference of expansion could be brought about as between shell 20 and rod 29, my objective might be achieved, at least in part.

By substituting Invar in place of copper as the metal from which shell 20 is composed, I accomplished at once a large expansion difference which resulted in a correspondingly substantial longitudinal movement of rod 29 in the appropriate direction to counteract the previously mentioned adverse effect of ambient temperature changes; and I discovered that the regulation which could thus be effected remained remarkably constant throughout the entire range of temperature variations which experience indicated were likely to be encountered.

The tuning of the cavity to correct for deviations from the assigned frequency, which is ordinarily accomplished by moving the plate rod longitudinally, is mainly a function of the movement of the lower end of the rod along the anode terminal 15a and is not to any substantial extent a direct function of the change in the length of the rod within the cavity. But, of course, the change of length of the rod within the cavity is the factor which determines the movement of the lower end of the rod, so far as this invention is concerned, and it will accordingly be apparent that the length of rod 29 within the cavity is a critical factor in determining the sufficiency of correction. In other words, if the rod is too long, within the cavity, it obviously over-compensates the frequency deviation and if it is too short, within the cavity, it will undercompensate said deviation. The length of rod outside the cavity is, manifestly, of no consequence.

To determine upon a design which will afford adequate regulation in any particular case, the most direct procedure is first to ascertain experimentally the extent of frequency deviation per degree of temperature change for the triode it is intended to employ when operating within the prescribed frequency band, and then determine how much movement of the plate rod is needed to offset the frequency deviation. Having ascertained that data and knowing the coefficients of expansion of the metals composing the plate rod and the shell respectively, it is a simple matter to compute the required effective length of the plate rod and thus arrive at a first approximation of a final design. Generally, it is most desirable to make the plate rod of copper or brass and the shell of Invar; but it is self-evident that the only indispensable requirement is that the rod must expand more than the shell to an extent sufficient to bring about the desired compensation.

If for any reason other than frequency regulation the plate rod must be made so long within the cavity that overcompensation would re-

sult when employing a structure like that of Fig. 1, resort may be had to the modification shown in Fig. 2 wherein the plate rod is made in two parts—the lower portion 36 being composed of copper or other metal having a large coefficient of expansion while the upper portion 37 may be composed of Invar. The two parts may be telescoped together as shown and secured by means of pins 38 or silver soldered. With such an arrangement the expandible portion of the plate rod can be made of precisely the right length to accomplish exact regulation while the necessary additional length is afforded by the Invar extension.

If the occasion should arise, it would be entirely feasible to make the shell 20 of two lengthwise adjoining parts, one being composed of Invar and the other of some other metal, such as copper. This would permit of a predetermined lengthwise expansion and contraction of the shell which could be used to offset excessive expansion and contraction of the plate rod in the event such an expedient be found necessary. Such a modification would not of necessity involve any structural change but merely a substitution of material throughout a portion of the length of shell 20. This obviously requires no additional illustration.

I claim:

1. An oscillation generator, comprising a tubular metal shell, a vacuum tube secured to one end of said shell and extending longitudinally therein, said tube having a cathode, a grid and an anode, the anode having an extending terminal, a metallic grid cylinder electrically connected to said grid and extending longitudinally within said shell toward the other end thereof, and a conductive member secured to said other end of said shell and extending longitudinally thereof into said grid cylinder in wiping engagement with said terminal, said member forming with said shell a coaxial line and also forming with said grid cylinder a second coaxial line, said shell and said member being composed at least in part of

5 materials having different coefficients of expansion to effect different variation in length of the portion of said member within said grid cylinder and said shell in response to temperature changes, whereby to counteract frequency deviations due particularly to the effects of such changes on the electrodes of said tube.

2. An oscillation generator, comprising a tubular metal shell, a vacuum tube secured to one end of said shell and extending longitudinally therein, said tube having an electrode terminal disposed within said shell, and a conductive member adjustably secured to the other end of said shell and extending longitudinally therein in wiping engagement with said terminal, adjustment of said member effecting tuning adjustment of the generator, said shell and said member being composed at least in part of materials having different coefficients of expansion to counteract frequency deviations due to temperature changes, and said conductive member comprising two serially connected sections composed of metals having different coefficients of expansion.
